PIPE

Hyman R. Segal, New York, N. Y.

Application January 7, 1935, Serial No. 606

11 Claims. (Cl. 131—12)

The present invention relates to an improved tobacco smoking pipe having means for circulating smoke fumes within the bowl prior to their travel in a mouth piece portion disconnectably associated with a tubular shank carried by the bowl.

The object of the invention is to provide a novel pipe in which the products of condensation of the smoke fumes originating in the bowl are initially collected in an annular smoke circulating chamber after which the products of condensation drain by gravity into a trap formed by complementary parts of the bowl.

The invention has as another object to provide a pipe comprising means for indirectly circulating the smoke fumes originating in the bowl by passing the fumes over a relatively large surface on which the products of condensation are initially deposited.

The invention has as another object the provision of a pipe having spaced annular members disconnectably relative to the base portion of the bowl and constituting means forming an internal vertically disposed annular chamber where the smoke is circulated to divide out or separate the moisture thereof before passing into the mouth piece portion to provide a relative cool and dry smoke.

The invention has as another object the provision of a pipe comprising inner and outer spaced annular members forming a vertical annular smoke circulating and cooling chamber, the inner member being disconnectably attached to a complementary portion of the bowl defining a hollow base and includes a horizontally disposed annular shoulder cooperating with the outer member to limit downward displacement of the latter and also provide an effective seal therewith to prevent smoke leakage.

Other objects, advantages and features of the invention are in part obvious and in part hereinafter pointed out and for a clearer understanding of the invention attention is directed to the embodiments shown in the accompanying drawings in which:

Fig. 1 is a view in elevation and partly in section of one form of pipe according to the invention.

Fig. 2 is a section on the line 2—2 of Fig. 1.

Fig. 3 is a vertical sectional view showing a slightly modified form of bowl.

Fig. 4 is a vertical sectional view of another modification.

Fig. 5 is an end view of Fig. 4 and

Fig. 6 is a section on the line 6—6 of Fig. 2 on a larger scale.

Fig. 7 is a section taken on the line 7—7 of Fig. 4.

According to the invention, the pipe illustrated in the several forms is generally designated 10. As shown each pipe comprises a housing 11 removably seated on a hollow base 12 from which extends a tubular shank 13 disconnectably carrying a conventional mouth piece portion or stem 14. For purposes of specification the housing 11 and base 12 may be considered as complementary parts constituting a bowl. 5

In the form shown in Figs. 1 and 2, housing 11 comprises two annular shells or members 15 and 16 integrally connected at their upper ends to define a solid rim 17. Shells 15 and 16 are suitably spaced apart to form an annular smoke circulating and cooling chamber 18. 10

Inner shell 16 is provided with an intermediate wall 19 forming therewith a pocket in which tobacco is sustained and depending from wall 19 is an annular rim 20 having external threads 21 adapted to disconnectably engage with internal threads 22 of upper rim 22' of base 12. 15

The wall 19 includes a pair of spaced diverging channels or orifices 23 and 24 which communicate with the interior of the inner shell 16 and the annular chamber 18. 20

The upper portion or rim 22' of the base 12 has a horizontal and flat annular face 25 which serves as a shoulder or stop for the lower portion 26 of outside shell 15 to limit rotational displacement of the housing relative to the base. 25

Lower portion 26 is provided with a knurled exterior surface 27 and the upper portion of base 12 also includes a knurled or roughened exterior surface 28 to prevent slippage of the manipulating fingers of the operator during adjustments of the housing relative to the base. 30

Smoke fumes originating within the inner shell are first drawn into channels 23 and 24 and subsequently travel upwardly within annular chamber 18 where they circulate to contact the walls of the chamber and deposit products of condensation or the like thereon. The fumes then pass downwardly into an inclined channel or orifice 29 through rim 22', the channel 29 being in communication with annular chamber 18 and reservoir or recess 30 formed in the hollow base 12. 35

Associated with base 12 and disposed transversely thereof and integral therewith is a wall 31 defining with the upper annular portion of the base a longitudinal disposed duct 32 in com- 40

munication with reservoir 30 and bore 33 of tubular shank 13.

Smoke entering reservoir 30 is subsequently directed through duct 32, bore 33, and the mouth piece portion 14 to the user. As the smoke circulates in chamber 18, it strikes the inclined vertical surfaces thereof which remove or separate the products of condensation. The particles of liquid deposited on these surfaces drain downwardly to the lower part of the smoke circulating chamber where they pass into channel 29 and from the latter fall by gravity into reservoir 30, it being noted that wall 19 together with annular depending rim 20 form a recess 34 having a continuous side wall 35 which facilitates any deposit of liquid particles to fall or drain into reservoir or concavity 30 and the retaining transverse wall 31 forms a baffle to prevent liquid within the reservoir to pass into shank 13. By reason of the action of wall 31 the hollow base 12 containing the reservoir may be considered as a trap in which products of condensation divided out or separated from the smoke are collected.

In the form according to Fig. 3, shells 15 and 16 are disconnectably associated. In this respect, the upper portion of the shells are provided with suitable threads as 36 to permit the outer shell to be adjusted relative to the inner shell. As shown in Fig. 3, a single inclined channel as 28 conducts the smoke fumes from the interior of the inner shell to the annular smoke circulating chamber 18 and a single inclined channel passing through the inner shell conducts smoke from chamber 18 into the reservoir 30. An annular flange or rib 40 extends from the base and serves as a stop to limit displacement of the inner shell thereon. In assembling, the inner shell is first connected to the base after which the outer shell is connected to the inner shell to abut shoulder 25.

In Figs. 4 and 5, housing 11 is along the lines of the construction illustrated in Fig. 3, except that shoulder 25 of rim 22 includes an upstanding boss 37 partaking of the curvature of the rim and provided with the spaced inclined outlet orifices or channels 38 and 39 for conducting the smoke from annular chamber 18 into the trap reservoir 30 while the inner shell comprises an inclined inlet channel 23 for conducting the smoke fumes from the interior thereof to the smoke circulating chamber 18.

If desired the base of the bowl may be provided with a reduced longitudinal portion 41 which serves as a hand grip to facilitate detaching the housing therefrom.

It is apparent that with the herein disclosed embodiments access may be readily had to the interior parts of the bowl to permit cleansing thereof or to remove deposited products of condensation accumulated in the trap. If desired the constructions illustrated may be made of any moldable insulating material, or of wood or of any other appropriate stock.

In the broader aspects of the invention, I do not desire to be understood as limiting its embodiments to details herein shown illustratively as a wide variety of modifications may be made within the scope of the appended claims without departing from the spirit of the invention.

70 I claim:

1. In a pipe, the combination of, a bowl comprising complementary parts, one part constituting a hollow base having an annular shoulder, the other part constituting a housing for receiving tobacco comprising spaced inner and outer

shells defining an annular smoke circulating chamber, said inner shell having a lower portion disconnectably secured to said base, said outer shell having a lower portion removably mounted on said shoulder, said inner shell having a channel for conducting smoke fumes from the interior thereof into said chamber, said bowl comprising means for conducting smoke fumes from said chamber into said base, and a shank carried by said base, said shank being adapted to 10 removably sustain a mouth piece portion.

2. In a pipe, the combination of, a bowl comprising complementary parts, one part constituting a hollow base having an annular shoulder, the other part constituting a housing for receiving 15 tobacco comprising spaced inner and outer shells defining a smoke circulating chamber, said inner shell having a lower portion disconnectably secured to said base, said outer shell having a lower portion removably mounted on said shoulder, said inner shell having a channel for conducting smoke fumes from the interior thereof into said chamber, means comprising a channel 20 for conducting smoke fumes from said chamber into said base, and a tubular shank carried by said base, said shank being adapted to removably sustain a mouth piece portion.

3. In a pipe, the combination of, a bowl comprising complementary parts, one part constituting a hollow base having a rim defining an annular shoulder, the other constituting spaced inner and outer shells forming an annular smoke 30 circulating chamber, said inner shell having a lower portion disconnectably secured to said rim, said outer shell having a lower portion removably seated on said shoulder, said inner shell having a channel for conducting smoke fumes from the interior thereof into said chamber, said bowl having an outlet channel for conducting smoke fumes from said chamber into said base, 40 and a tubular shank carried by the latter, said shank being adapted to removably sustain a mouth piece portion.

4. In a pipe, the combination of, a bowl comprising complementary parts, one part constituting a hollow base having a rim defining a shoulder, the other part constituting spaced inner and outer shells forming a smoke circulating chamber, said shells having their upper portions integrally connected, said inner shell having a lower portion disconnectably secured to said rim, said outer shell having a lower portion removably mounted on said shoulder, said inner shell having a channel for conducting smoke fumes from the interior thereof into said chamber, said bowl having an outlet channel for conducting smoke fumes from said chamber into said base, and a tubular shank carried by the latter, said shank being adapted to removably sustain a mouth piece portion.

5. In a pipe, the combination of, a bowl comprising complementary parts, one part constituting a hollow base having a rim defining a shoulder, the other part constituting spaced inner and outer shells forming a smoke circulating chamber, said shells having their upper portions disconnectably secured, said inner shell having a lower portion disconnectably secured to said rim, said outer shell having a lower portion removably seated on said shoulder, said inner shell comprising a channel for conducting smoke fumes from the interior thereof into said chamber, said bowl having an outlet channel for conducting smoke fumes from said chamber into said base, and a tubular shank carried by the 70 75 75

latter, said shank being adapted to removably sustain a mouth piece portion, said base having an inwardly disposed overhanging flange to limit downward displacement of said inner shell relative to said base.

5. In a pipe, the combination of, a bowl comprising complementary parts, one part constituting a hollow base having a rim defining an annular shoulder, the other constituting spaced inner and outer shells forming an annular smoke circulating chamber, said inner shell having a lower portion disconnectably secured to said rim, said outer shell having a lower portion removably seated on said shoulder, said inner shell comprising a channel for conducting smoke fumes from the interior thereof into said chamber, said rim having an outlet channel for conducting smoke fumes from said chamber into said base, and a tubular shank carried by the latter said 10 shank being adapted to removably sustain a mouth piece portion, said base having a trap to receive products of condensation from said smoke draining from said chamber said base having an inwardly disposed overhanging flange to limit downward displacement of said inner shell relative to said base.

7. In a pipe, the combination of, a bowl having a base comprising a rim having a continuous shoulder and including a concavity, a baffle disposed across said concavity, an inner shell having its lower portion threadably secured to said rim, an outer shell carried by said inner shell and spaced therefrom to define a smoke circulating chamber, said outer shell having a lower portion removably seated on said shoulder, said inner shell having an inlet channel for conducting smoke therefrom into said chamber, said bowl having means for conducting smoke from said chamber into said concavity, and a shank, adapted to removably sustain a mouth piece portion, said concavity constituting a trap for collecting moisture draining from said chamber, said base having means to limit downward displacement of said inner shell relative to said base.

8. In a pipe, the combination of, a bowl having a base comprising a rim having a continuous shoulder and including a concavity, a baffle forming a wall of said concavity, an inner shell having its lower portion removably secured to said rim and having a wall forming a closure for said concavity, an outer shell carried by said inner shell and forming therewith a smoke circulating chamber, said outer shell having a lower portion removably seated on said shoulder, a boss carried by the latter and including smoke conducting means permitting smoke within said chamber to pass into said concavity, said inner shell hav-

ing a channel to conduct smoke from within the interior thereof to said chamber, and a shank carried by said base, and adapted to removably sustain a mouth piece portion.

9. In a pipe, the combination of, a base having an annular shoulder and a trap, an inwardly disposed annular shell threadably secured at its lower end to the base and extending upwardly from said base, said shell having a channel in communication with the interior and exterior surfaces thereof, an outer shell carried by said inner shell and having a lower portion annularly seated on said shoulder, said shells defining a smoke circulating chamber in communication with said channel, said base having a channel in communication with said chamber and trap, and a tubular shank in communication with said trap and adapted to removably sustain a mouth piece portion.

10. In a pipe, a bowl comprising a base having an annular shoulder, an inwardly disposed shell extending upwardly therefrom, said shell having a channel in communication with the interior and exterior surfaces thereof, an exterior annular shell disconnectably associated with said inner shell and having a lower portion seated on said shoulder, said shells defining a smoke circulating chamber in communication with said channel, and a tubular shank carried by said base and adapted to removably support a mouth piece portion, said base having a channel in communication with said chamber and the bore of said shank, said base having an inwardly disposed overhanging flange to limit downward displacement of said inwardly disposed shell relative to said base.

11. In a pipe, the combination of, a bowl having a base comprising a rim having a continuous shoulder and including a concavity, a perforated baffle forming a wall of said concavity, an inner shell having its lower portion removably secured to said rim and having a wall forming a closure for said concavity, an outer shell carried by said inner shell and forming therewith an inwardly disposed annular smoke circulating chamber, a boss projecting from said shoulder and integral with said base, said outer shell having a lower portion removably seated on said shoulder and surrounding said boss, said inner shell having a channel to conduct smoke fumes from the interior thereof into said chamber, said bowl having means to conduct smoke fumes from said chamber into said concavity and a shank carried by said bowl adapted to disconnectably sustain a mouth piece portion.
